UNITED STATES PATENT OFFICE.

WARREN A. MORRIS, OF WYOMING, OHIO, ASSIGNOR TO THE RICHARDSON COMPANY,
OF LOCKLAND, OHIO, A CORPORATION OF OHIO.

CARTON.

Application filed July 5, 1927. Serial No. 203,440.

My invention relates to cartons, and particularly to cartons having dispensing spouts formed in cut and scored portions of the carton assemblies.

5 It is the object of my invention to provide a carton having overlapping portions which normally form a closure for the package within the walls of which a dispensing spout is outlined in cut and scored lines, or in other 10 readily frangible lines such as may be provided by perforations. It is further my object to provide a carton made from a cut and scored blank having a dispensing spout in the closing flaps thereof, which may be set 15 up on the ordinary sealing machine without the requirement of any additional mechanism. I propose to form walls of a dispensing spout in what are ordinarily the top closing flaps of the carton, and to seal these flaps 20 on a mechanical bottom sealer first, and to then fill the carton bottom side up, and finally to close in and seal the bottom closing flaps after the carton is filled. While I find such a procedure most practical from a 25 manufacturing point of view I have so formed the cut and scored portions in the top closing flaps that these closing flaps may be closed in and sealed either before or after the filling of the carton.

30 I have as a further object the provision of a dispensing spout formed in an underlying portion of a carton in which an outer overlapping portion has a withdrawal tab so shaped that the proper folding of the side walls of the dispensing spout which is to be withdrawn through the aperture outlining the tab in the outer overlapping portion along predetermined lines, will be enforced.

A further object is the disposition of non-adhesive areas on the overlapping portions so that a continuous application of glue over portions which are to be overlapped will not cause all the surfaces to which the glue is applied to become adhesive.

The above and other objects to which reference will be made during the ensuing disclosure, I accomplish by that certain arrangement and combination of parts of which I have shown a preferred embodiment.

In the drawings:—

Figure 1 is a plan view of the cut and scored blank from which the carton illustrated is made.

Figure 2 is a top plan view of the carton with the end closure flaps folded in. 55

Figure 3 is a plan view of the carton with the end and one of the side flaps folded in.

Figure 4 is a plan view of the carton with the end and both side closing flaps folded in.

Figure 5 is a side elevation of the carton 60 with the dispensing spout flap withdrawn.

Figure 6 is an end elevation of the carton shown as in Figure 5, with the dispensing spout withdrawn.

Figure 7 is a sectional view on an enlarged 65 scale along the lines 7—7 in Figure 6.

The carton is made from a blank having side pieces 1 joined integrally with end pieces 2 by lines of articulation indicated at *a—a*. I have further shown the extension 3 which 70 provides means for attaching the portion 1 shown to the left in Figure 1 to the portion 2 shown to the right in Figure 1. Extending from the side walls I have shown the closure flaps 4, and extending from the end walls, 75 the closure flaps 5. The type of carton to which my invention is applied has no particular importance, as the dispensing spout closure which I have provided may be formed in any walls of a carton in which there are 80 overlapping portions.

I have selected the top closing flaps in which to outline in cut and scored lines, my novel dispensing spout 6, as I find that such an arrangement provides the most practical 85 position from the point of view of usefulness.

The end closure flap 5, as indicated, has a curved line *b—b* which outlines the base and side walls of a dispensing spout. The side walls are formed by cut lines indicated at 90 *c—c*, and the back wall of the base of the

spout is outlined by the line *d—d*, the walls of the wing-like sides 7 of the dispensing spout being outlined by portions of the cut lines *b—b* and the score lines *e—e*. The 95 shaded area *f—f* is covered with a neutral printing ink or other suitable substance to prevent the adhesion thereto of glue during the sealing of the closure flaps. An application of paraffin over the area *f—f*, for example, will also impart nonadhesive properties. I may prefer to leave a minute uncut portion in the line *b—b* in the center of its arc, in order to facilitate sealing the carton on the ordinary sealing machines. 100

I have shown both side closing flaps 4—4,

having withdrawal tabs 8 formed with cut lines $g-g$ outlining the front and sides of the tabs, and with lines $h-h$ along the line of attachment to the flaps 4-4. When the side walls are folded over, the lines $h-h$ should lie substantially in alignment with the line $d-d$. It should be noted that the cut lines which outline the sides of the withdrawal tabs taper out somewhat from the line of attachment toward the open end. The reason for extending the lines of cut which outline the sides of the withdrawal tabs in such directions is so that when the dispensing spout is withdrawn through the withdrawal tab openings the score lines $e-e$ which form the lines of attachment of the dispensing spout side walls to the base of the spout will be gradually folded back without liability of bending improperly or tearing off.

It will be observed that the size of the withdrawal tab in the side closure flap 4 to the left in Figure 1 is slightly smaller than the withdrawal tab in the flap 4 which is shown at the right. It is preferable to have the withdrawal tab on whichever flap 4 is closed in first on the end flap 5, of relatively smaller proportions. The principle to be observed in this connection is that no perfect folding of the flaps will ever occur, so when an inner part is required to pull out through an opening in an outer one, by making the outer one slightly larger than the inner one, there will be no likelihood of improper or imperfect registry.

In the drawings, the flap shown to the left in Figure 1 is supposed to fold over first on the end flaps. The tapering of the cut lines outlining the sides of the withdrawal tab is only necessary on that flap which is to lie against the end flap. In Figure 1 the closing flap to the left is the one of the flaps in which the tapering of the lines outlining the side of the withdrawal tabs enforces easy bending of the score lines which form the line of articulation of the side walls and the base of the dispensing spout. The tapering of the side walls of the withdrawal tab on that one of the side closure flaps which is to be folded over and sealed last is merely for purposes of clearance and to prevent registry of cut lines which might cause leakage.

The sealing of the top closing flaps of the carton is preferably performed on a bottom sealer. One well known type of bottom sealer has a roller which first folds down and applies a layer of glue to the end closure flaps. Then the machine has another roller which moves sideways across the carton and folds down one of the side flaps, to which glue is also applied. The other side closure flap is then folded over and pressure is applied to the outer surface of the last flap, and, since the carton is normally carried on a block which fits the shape of the inside of the carton, a good tight sealed joint can be made.

The treatment of the upper surface of the

dispensing spout to make the board non-adhesive to glue prevents the wings of the dispensing spout from adhering to the under surface of the first one of the side closure flaps which is to be folded over on it.

While I have shown my dispensing spout and withdrawal tab arrangement with the dispensing spout on the underneath one of three overlapping portions of the carton, it is within the scope of my invention to vary the position of the dispensing spout with relation to the withdrawal tabs. The dispensing spout might be formed in one of the side closure flaps.

Other modifications of the structure shown will readily occur to those skilled in the art without departing from the principle involved.

For withdrawing the spout a pointed instrument should be inserted at the open end of the outer withdrawal tab, and the spout assembly can be withdrawn for use. The lines which outline the walls of the withdrawal tabs and dispensing spout being out of registry will not allow powdered material to leak out from within the carton.

Having thus described my invention, what I claim as new and desire to secure by Letters Patent, is:—

1. A carton having at least three overlapping portions, and having a base and side walls of a dispensing spout outlined in cut lines in an underlying portion, with withdrawal tab portions outlined in overlying overlapping portions.

2. A carton having at least three overlapping portions, and having a base and side walls of a dispensing spout outlined in cut lines in an underlying portion, with withdrawal tab portions outlined in cut lines in overlapping portions.

3. A carton having at least three overlapping portions, and having a base and side walls of a dispensing spout outlined in cut lines in an underlying portion, with withdrawal tab portions outlined in cut lines in overlapping portions, said dispensing spout having a base articulated to an underlying portion, and said withdrawal tabs having lines of articulation formed to register with the line of articulation of the base of the dispensing spout and the underlying portion to which it is attached.

4. A carton having overlapping portions in which an underlying portion has a dispensing spout outlined in readily frangible lines, said dispensing spout having a base with sides articulated thereto, and a portion overlying said portion having a withdrawal tab formed in readily frangible lines, the outline of the withdrawal tab being slightly larger than the base of the spout, and the surface of an engaging face of at least one of said overlapped portions treated so as to be impervious to glue adhesion, whereby the sides of the spout

will not adhere to an overlapped portion during the sealing of the overlapping portions, one on another.

5. A carton having overlapping portions in which an underlying portion has a dispensing spout outlined in readily frangible lines, said dispensing spout having a base with sides articulated thereto, and a portion overlying said portion having a withdrawal tab formed in readily frangible lines, the outline of the withdrawal tab being slightly larger than the base of the spout, and the surface of an engaging face of at least one of said overlapped portions treated so as to be impervious to glue adhesion, whereby the sides of the spout will not adhere to an overlapped portion during the sealing of the overlapping portions, one on another, and the outline of the withdrawal tab being tapered from base 20 to front to facilitate the bending of the sides of the base of the dispensing spout during withdrawal of the spout.

6. A carton having at least three overlapping portions forming an end closure with a dispensing spout outlined in readily frangible lines in an underlying portion, said dispensing spout having a base and articulated wing-like sides, withdrawal tabs formed in overlapping portions, said tabs being of such size 30 as to admit the withdrawal therethrough of said spout base with the wings thereof folded at right angles to said base, said withdrawal tabs being successively of larger size than said spout base, whereby the spout base may readily pass through the innermost of the open-

ings formed by the withdrawal tab in the undermost of those overlapping portions having tabs therein, and whereby the undermost withdrawal tab will readily pass through the opening in the overlapping portion in which 40 the outermost withdrawal tab is formed.

7. A carton having at least three overlapping portions forming an end closure with a dispensing spout outlined in readily frangible lines in an underlying portion, said dispensing spout having a base and articulated wing-like sides, withdrawal tabs formed in overlapping portions, said tabs being of such size as to admit the withdrawal therethrough of said spout base with the wings thereof 50 folded at right angles to said base, said withdrawal tabs being successively of larger size than said spout base, whereby the spout base may readily pass through the innermost of the openings formed by the withdrawal tab in the undermost of those overlapping portions having tabs therein, and whereby the undermost withdrawal tab will readily pass through the opening in the overlapping portion in which 55 the outermost withdrawal tab is formed, and the upper surface of the first mentioned underlying portion treated so as to have areas thereof in which the wing-like sides of the spout are formed, which will be impervious to glue adhesion so that the closure flaps may be sealed with a uniform layer of glue applied to the overlapping portions during the sealing operation.

WARREN A. MORRIS.
